UNITED STATES PATENT OFFICE.

WILLIAM H. PUTNAM, OF BROOKLYN, NEW YORK.

ANTISKIDDING DEVICE FOR VEHICLES.

1,223,070.

Specification of Letters Patent. Patented Apr. 17, 1917.

Application filed September 18, 1916. Serial No. 120,618.

To all whom it may concern:

Be it known that I, WILLIAM H. PUTNAM, a citizen of the United States of America, and resident of Brooklyn, in the county of

5 Kings and State of New York, have invented certain new and useful Improvements in Antiskidding Devices for Vehicles, of which the following is a full, clear, and exact description.

10 This invention is in further development of, and improvement on, anti-skid devices for automobiles or other vehicles of the character shown, described and claimed in Letters Patent of the United States granted 15 to me Nov. 26, 1912, No. 1,045,609, and Aug. 17, 1915, No. 1,150,148.

An object of the invention is to provide improved means on the wheel of an automobile in engagement with which runs the 20 roller which carries the centrifugally operating flexible members to be thrown more or less nearly radially and to engage under the tread of the wheel, which improved means more advantageously and effectually 25 insure the operation of the flexible member carrying roller.

Another object of the invention is to provide improved means for controlling the positions of the flexible member carrying roller 30 which is to have its position of frictional engagement with the wheel and a position of retirement and disengagement from the wheel.

Another object is to improve the anti-skid 35 device specifically in respect to the construction of the flexible members comprised therein.

Other objects of the invention are attained in and by constructions and devices 40 herein shown and described.

In the drawings:—

Figure 1 shows a sectional elevation, as seen from the inside, of one of the rear wheels of an automobile and the improved 45 devices in operative relation thereto.

Fig. 2 is a sectional view in detail showing parts as seen on and beyond the plane indicated by line 2—2, Fig. 1.

Fig. 3 is a vertical sectional view as seen 50 taken on line 3—3, Fig. 1, but showing the flexible member carrying roller as in its operative relation to the wheel.

Fig. 4 is a plan view of a portion of the vehicle comprising and adjacent one wheel thereof and showing the improved device 55 thereon.

Fig. 5 is a sectional elevation showing the chauffeur's controlling lever and a portion of the operating connection.

Fig. 6 shows a face view of lever and detent devices otherwise shown in Figs. 1 and 2.

Figs. 7 and 8 are respectively a face and a sectional view of elements comprised in the improved flexible roller-carried members. 65

Figs. 9 and 10 are respectively a plan view and an elevation showing housing provisions for the anti-skid device when in its position of disuse.

Fig. 11 is an elevation showing a device 70 for clearing the surface of the wheel carried friction ring.

In the present device the flexible member-carrying roller A instead of being arranged for peripheral frictional bearing on the tire 75 of the traction wheel B of the automobile is so mounted as to have, at pleasure, frictional bearing, suitably near the ground bearing portion of the wheel, on a ring provided for such purpose and carried on the face of the 80 wheel.

As the device has been carried out in actual construction and for an important advantage, the ring is sectionally made whereby one of the sections is comparatively freely 85 revoluble relatively to the wheel.

The flexible members or chains have a tendency to grind or work out from under the tread while the wheels are locked under the setting of the brakes, permitting the car 90 to advance on a forward skid,—there being, of course, when the wheels are locked, a stoppage of the rotation of the roller and consequently of the centrifugal throw of the 95 chains.

Now the object of having the ring on which the roller frictionally bears movable relatively to the wheel, is to insure that the antiskid device will still turn and remain operative after the wheels have been locked 100 and stopped by the action of the brakes.

In the actual construction as made and used, a ring C is securely affixed on the inner side of the wheel, concentric with the

axis, its attachment as shown being by staple shaped clips *a* for engagements with the spokes of the wheel and the nuts *a*².

This ring is provided with a laterally projecting rib or flange *b* having a beveled periphery *b*² which is encircled with a suitably close fit by a second ring *c* arranged on the same side of the wheel and loose relatively to the wheel and the first named ring 10 and provided with a flange *c*² which is inclined or oblique to the plane of rotation of the wheel and adapted for frictional engagement with the beveled peripheral portion of the ring section *C*.

15 *d* represents a retaining ring, separately made from the ring *c* but rigidly secured thereto by the screws or bolts *d*², to constitute, in effect, a rigid flange, supplemental to the flange *c*² of the ring *c* to overlap on 20 the face of the beveled portion *b* of the wheel affixed ring *C*.

The outer marginal portion *c*³ of the independently revoluble ring *c*² is turned or inclined obliquely to the plane of the wheel 25 for receiving frictional engagement thereon of the edge of the antiskid roller *A* which has a position, in its presentation for the frictional bearing substantially at right angles to the surface of the portion *c*³, and, 30 of course, also oblique to the plane of the wheel.

The aforementioned peripherally beveled portion *b* of the ring *C* is provided with a plurality of sockets *f* opening to the edge 35 of the ring and receiving springs *e* therein, in compression and reacting against the supplemental ring *d* preferably through the medium of interposed bearing blocks *e*².

Means are provided for the introduction 40 of lubricant into the spring sockets, such for instance, as the oilers or cups *g*; and a duct *g*² leads from each spring socket to the beveled periphery of the part *b*, whereby the ring *c* may be suitably free relatively to 45 the ring *C*.

The springs *e* exerting a pressure outwardly against the retaining ring always insure a frictional contact on what may be regarded as the "cone bearing" portions of 50 the device, insuring that the independently revoluble ring will partake of the motion of the wheel as soon as power is applied, for imparting motion to the antiskid roller.

Yet this frictional contact or engagement 55 of the ring *c* relatively to the portion *b* of the wheel-affixed ring is not sufficiently effective to prevent a continuing of revolution of the ring *c* when the brake is applied and the turning of the wheel stopped.

60 The great increase in efficiency of the device embodying the last described provisions so far supersedes the added cost of the equipment as to render the latter inconsequential.

The anti-skid roller *A* having dependent 65 studs *h* to which the flexible centrifugally acting members *m* are secured is mounted on a hub-shaped or boss-shaped extremity *n*² of an arm *n* which is carried on a stud or rockshaft *n*³, mounted for its rocking 70 movement in a journal provided portion at the forward end of a bracket *D*, rigidly, though removably, secured to the rear axle housing and projecting forwardly thereof. 75

The journal bearing portion *D*² at the forward extremity of the bracket *D* is axially oblique to the longitudinal and transverse lines of the vehicle so that the arm *n* and the roller carried thereby, in the oblique relations indicated have swinging movements from the withdrawn, or inoperative relations shown in full lines in Fig. 1 to the operative relations shown by the dotted lines in Fig. 1, and by the full lines in Figs. 3 and 4. 80

The roller carrying arm *n*, from its junction or connection with the stud or short rockshaft *n*³, is downwardly inclined for a suitable way, is thence continued at an obtuse angle and terminates in an upwardly inclined portion, as the same is viewed in the full line representation thereof in Fig. 1,—the same in other words being of a bowed form to afford clearance from the axle housing, by the arm, when the antiskid roller is retired and occupies a position about at the level of and to the rear of the axle whereby the flexible members or chains will be well clear from the ground. 90

The arm carrying short stud or rockshaft *n*³ has at the opposite end of the journal bearing hub *D*² from that of the arm a more or less nearly vertically extended rigidly affixed lever *E*, to a portion of which a second lever *F* is connected by pivot *o*. 95

This lever *F* as seen comprises a long arm above the pivot and a short arm below the pivot and which short arm is formed to constitute a round ended pawl *p*. 100

The lever *F* swings relatively to the lever *E* in the same plane as that of the swinging motion of the lever, *E*; the pawl *p* cooperates with a ratchet-like member or detent shoulder *q* formed on the journal hub *D*² of the bracket; and a spiral spring *G* in compression is applied and reacts between the levers *E* and *F*. 110

An abutment *r* on the lever *E*, and extending toward the lever *F*, serves as a means for limiting the extent of the swinging movement of the pawl provided lever relatively to the lever which is appurtenant to the roller carrying arm. 120

H represents a chauffeur's lever understood as mounted near and accessible from the driver's seat, the same comprising an upwardly extending handle arm, a pivotal member and a downwardly extending arm to 125

which is attached the cable J rearwardly extended for connection with the upper end of the pawl-provided lever F.

As a means for providing for the control of duplicated anti-skid devices for the opposite rear wheels of the automobile, the chauffeur's lever H is affixed to and radially upwardly extended from a transverse rock-shaft K suitably mounted on the body and 10 which rockshaft has duplicated depending arms H² for actions and results as manifest.

Assuming the anti-skid device is in its upwardly swung position shown by full lines in Fig. 1 and retained by the engagement of 15 the pawl p with the ratchet or detent shoulder q, to release the device and permit the roller to be swung for a frictionally bearing operative position, the chauffeur's lever is pulled back from the normal position 1 (indicated in Fig. 1) to the dotted line position, 2.

This swings the secondary lever F to the limit as determined by the abutment, compresses the spring G and swings the pawl 25 out of engagement with the ratchet-like shoulder q.

Now the pawl being clear of the ratchet, the weight of the antiskid roller falls upon the chauffeur's lever and as such weight is 30 greater than the pressure necessary to compress the spring G and release the pawl, it is only necessary to permit the chauffeur's lever to be swung to its extreme forward position represented by 3 in the dotted line 35 indication at the right hand portion of Fig. 1, and under proper checking restraint by the hand of the chauffeur for the prevention of too violent impact of the anti skid roller in coming to its operative contact relation to 40 the ring c on the wheel.

While the parts are in the operative positions or relations the pawl p has assumed a position around on the inclined back of the ratchet-like member and behind the engagement 45 face or shoulder of the latter.

Now to withdraw the device to its position of inaction, a comparatively short pull is given to the chauffeur's lever, that is one from position 3 to position 4.

50 This is to be a comparatively slow pull and to cause the release of the chain or flexible members from under the wheel, which it may be assumed is turning.

When the flexible members shall have become free, which will be almost instantaneously performed, and which the driver will be aware of from the lessening of resistance 55 on the chauffeur's lever, such lever is then given a sharp swinging movement,—not the full length of the possible pull,—in a manner to cause the cable to become slackened and the lever F to be swung under the reaction of the spring to permit the pawl to 60 snap into engagement with the ratchet tooth.

To recapitulate these controlling operations with respect to the positions of the chauffeur's lever: Position 1 is the normal position,—the parts retired and restrained; position 2 is that of the lever when the spring is compressed, the ratchet disengaged 70 and the antiskid device freed to be lowered; position 3 is that of the lever when the anti skid device is in its operative position; position 4 is that to which the lever is gradually drawn for effecting the withdrawal of 75 the flexible members from under the tread of the wheel and from which to the position 1 the lever is moved with a sharp jerk and release for slackening the cable, relieving the counter force on the spring and allowing the 80 pawl to assume its engagement with the ratchet or detent shoulder.

The chauffeur's lever may be a hand or foot actuated device as may be preferred.

A manually acting lever is, however, generally to be preferred to a foot lever as being somewhat better susceptible to the manipulations necessary for the peculiar controlling actions to be imparted to the roller carrying arm, and especially to enable in the 90 withdrawing of the anti-skid device on the final forward movement of the lever, the proper action to enable the cable, even under a draft-imparting strain to become slackened.

In the final pulling movement with a quick jerking action, the draft on the cable is of a character to initially impart such a toss or impetus to the roller-carrying arm as 100 to cause it and the lever arms to advance relatively to the cable, to thereby slacken or relieve the strain on the cable and to enable the spring G to react and set the pawl.

Inasmuch as the roller carrying arm is thrown upwardly, for its retirement, more 105 or less violently toward or against the axle, the arm is provided at an intermediate portion thereof with a buffer s to act as a cushion between the arm and axle and for absorbing the shock.

L represents a spring arm or clip mounted on a suitable fixed supporting part, as, for instance, the bracket D near its connection with the axle housing and which extends in a downward and forward direction, and obliquely so as to exert a resilient impingement against the roller carrying arm when lowered, for holding or steadyng the arm and therewith the roller in its continuous frictional engagement with the ring on 115 the wheel.

Inasmuch as some persons would prefer to remove the anti-skid roller in dry weather, I have provided a construction whereby the roller is detachably held on the boss shaped 120 extremity of the arm n.

The said boss shaped extremity, as shown, in Fig. 3, is provided with a downwardly

opening socket t therein, the wall surrounding said socket having radially arranged opposite apertures t^2 therethrough.

The roller A has therefor a central stud u on which it rotates, being supported by the flange u^2 , said stud being upwardly extended to fit in said socket, and it is provided with recesses v therein to match with the aforementioned radial apertures t^2 .

10 w represents a retaining device indicated as being formed of a length of wire, an intermediate portion of which is return bent to comprise double collar-like members to encircle the boss shaped arm extremity while 15 the extremities of said wire are downwardly and then radially inwardly extended for detachably engaging in the apertures t^2 and v in the stud.

10 The roller hub is to be provided with a bushing driven or tightly fitted therein; and 20 the roller supporting and bearing stud u is made hollow and upwardly opening,—the cavity in the stud constituting a lubricant receptacle; and the stud has a radial duct u^4 25 through the lower portion thereof which is surrounded by the roller A for lubrication of the bearing surfaces, that is the exterior of the stud and the internal surface of the bushing which is appurtenant to the roller. 30 The roller stud has mounted on it a washer u^5 which houses a dust excluding felt annular piece u^6 .

35 The upper end of the socket or oil receiving cavity in the stud may be provided with a cork or other stopper or closure.

40 The anti-skid roller A advantageously comprises a peripheral bearing portion or tire A^2 which is demountable or interchangeable,—this tire being mounted on a tire rim 45 separate from and circumferentially fitting the body of the roller and confined thereon by headed and nut-provided bolts A^4 and clamping washers A^5 .

45 The construction of my improved devices is such that they may be altogether removed from the automobile, and reattached at pleasure, or parts only thereof may be removed or rendered inoperative, for example, the anti-skid roller may be temporarily removed from its carrying arm as hereinbefore stated; but when the roller is so removed the ring c on which it frictionally bears, during use, may be locked against its revolute movement relatively to and independently of the wheel; and as a provision to this end, a set screw x (Fig. 3) is shown as having a screw thread engagement in a tapped hole therefor in the supplemental ring d , carried as a flange thereof by the 55 ring c .

50 By turning this screw inwardly to engage the outer edge of the portion b of the wheel affixed ring C , the ring c becomes immovable relatively to the wheel.

60 65 The flexible members m of the antiskid

device include elastic members to permit them to be endwise distensible and contractible; and in Figs. 3, 7 and 8 an improved form of link member is shown, the same consisting of an annular body or link m^2 understood as made of elastic rubber with which one of the links of the chain is engaged, and with which also is connected a swivel m^3 having an eye m^4 connected with the depending members h of the roller.

70 The portion of the rubber link member m^2 through which the shank of the swivel is passed is provided with a link m^5 of thin metal and of curved or arc form and provided with opposite side lips m^6 engaging 75 the faces of the rubber link.

75 The head or shoulder m^7 of the swivel is in direct engagement against such lining, which latter reinforces and strengthens the link in a manifest manner.

80 The provision of the swivel as the medium of connection between each flexible member and the roller prevents the flexible members from becoming twisted in their anti-skidding operations and at all other times.

85 Inasmuch as there is a tendency of leakage and throwing of dirty oil or grease from the brake rings of the wheels, more or less near to which the antiskid device is located, and more or less of which oil or grease as 90 well as other obstructive matter, comes onto the frictional bearing ring on the wheel, I have provided a clearer or scraper member N for engagement on the beveled portion c^3 of the ring.

95 100 This scraper is fixed on a boss N^2 on the journal bearing portion D^2 of the bracket or other suitable fixture therefor; and as the use thereof is to be only temporary, it is adjustable so as to be swung from its operative position relatively to the ring, toward the center of the car and away from such ring by merely loosening and retightening the screw N^8 .

105 Figs. 9 and 10 represent the housing for 110 each roller when drawn up out of engagement with the wheels.

110 This housing is made in the form of a box or casing P , supported by an arm P^2 mounted on or connected to a part of the bracket 115 D ; and it has a tilting back or cover Q hinged at Q^2 and to be normally closed by a spring applied to the hinge in the usual manner employed in spring hinged covers.

120 The cover or back Q is of curved form as represented at Q^3 so as to also form a closure for one end of the casing or housing.

125 The anti-skid roller when raised will strike a curved part of the movable back Q , forcing the back open to permit the entrance of the device therein, whereupon the back will swing into its normally closed position, gathering the chains in the depression Q^4 comprised in the reversely curved part Q^3 .

130 This casing or housing may be provided

with a lining to prevent or lessen the rattling of the chains.

I claim:

1. In a device of the character described, 5 the combination with a vehicle wheel having a ring on the side thereof which is circumferentially movable relatively to the wheel, of a roller mounted to have the edge thereof in frictional bearing on said ring, and 10 provided with a plurality of flexible members adapted under centrifugal force to be thrown more or less nearly radially and to engage under the tread of the wheel.
2. In a device of the character described, 15 the combination with a vehicle wheel having a ring on the side thereof which is circumferentially movable relatively to the wheel, and means for imparting a frictional engagement between the wheel and ring, of a 20 roller mounted to have the edge thereof in frictional bearing on said ring, and provided with a plurality of flexible members adapted under centrifugal force to be thrown more or less nearly radially and 25 to engage under the tread of the wheel.
3. In a device of the character described, the combination with a vehicle wheel having a ring on the side thereof which is normally circumferentially movable relatively to the 30 wheel, of a roller mounted to have the edge thereof in frictional bearing on said ring, and provided with a plurality of flexible members adapted under centrifugal force to be thrown more or less nearly radially and 35 to engage under the tread of the wheel, and means for temporarily confining said ring non-revolubly relatively to the wheel.
4. In a device of the character described, 40 in combination, a wheel having a ring section fixed on the side thereof and provided with a laterally protruding portion having a beveled or conical periphery, another ring section arranged on the side of the wheel and loose relatively to the wheel and the first 45 named ring section and provided with a portion adapted for frictional engagement with the beveled portion of the said named ring section and means for retaining the second ring section relatively to the first 50 ring section, and a roller mounted to have the edge thereof in frictional bearing on said second ring section and provided with a plurality of flexible members adapted to be centrifugally thrown and to engage under the 55 tread of the wheel.
5. In a device of the character described, 60 in combination, a wheel having a ring section fixed on the side thereof and provided with a laterally protruding portion having a beveled periphery, another ring section arranged on the side of the wheel and loose relatively to the wheel and the first named ring section and provided with an inclined flange adapted for frictional engagement 65 with the beveled portion of the first named 70 ring section, a retaining ring, secured to the edge of said flange, and overlapping the edge of said beveled portion of the first ring section, and a roller mounted to have the edge thereof in frictional bearing on the said second ring section and provided with a plurality of flexible members adapted to be centrifugally thrown and to engage under the tread of the wheel.
6. In a device of the character described, 75 in combination, a wheel having a ring section fixed on the side thereof and provided with a laterally protruding portion having a beveled periphery, another ring section arranged on the side of the wheel and loose 80 relatively to the wheel and the first named ring section and provided with an inclined flange adapted for frictional engagement with the beveled portion of the first named ring section, a retaining ring, secured to the edge of said flange, overlapping the edge of said beveled portion of the first ring section, and a set screw provided to the retaining ring, and adapted to lock it, and the second ring section to the first section, and a roller mounted to have the edge thereof in frictional bearing on the said second ring section and provided with a plurality of flexible members adapted to be centrifugally thrown and to engage under the tread of the 85 wheel.
7. In a device of the character described, 90 in combination, a wheel having a ring section fixed on the side thereof and provided with a laterally protruding portion having a beveled periphery, made with a plurality of spring sockets therein, another ring section arranged on the side of the wheel and loose 95 relatively to the wheel and to the first named ring section and provided with a portion adapted for frictional engagement with the beveled portion of the first named ring section and also provided with a flange-forming member overlapping the edge of said beveled and socketed portion, and springs in compression in said sockets and reacting against said flange-forming member, and a roller mounted to have the edge thereof in frictional bearing on said second ring section and provided with a plurality of flexible members adapted to be centrifugally thrown and to engage under the tread 100 of the wheel.
8. In a device of the character described, 105 in combination, a wheel having a ring section fixed on the side thereof and provided with a laterally protruding portion having a beveled periphery, made with a plurality of spring sockets therein, another ring section arranged on the side of the wheel and loose 110 relatively to the wheel and to the first named ring section and provided with a portion adapted for frictional engagement with the beveled portion of the first named ring section and also provided with a flange- 115

forming member overlapping the edge of said beveled and socketed portion, and springs in compression in said sockets and reacting against said flange-forming member, and the said beveled and socketed portion of the wheel attached rim having means for supplying oil into the sockets, and having oil ducts leading from the sockets to the surface of the beveled portion of such ring, 5 and a roller mounted to have the edge thereof in frictional bearing on said second ring section and provided with a plurality of flexible members adapted to be centrifugally thrown and to engage under the tread of 10 the wheel.

9. In a device of the character described, the combination with a vehicle wheel having a ring on the side thereof provided with a flange inclined to the plane of such 20 side of the wheel, of a roller adapted to have an operative position oblique to the plane of the wheel and substantially perpendicular to the face of said inclined flange and to frictionally bear on the latter, and 25 provided with a plurality of flexible members adapted to be centrifugally thrown for engagements under the tread of the wheel.

10. In a device of the character described, a vehicle wheel having a ring on the inner 30 side thereof provided with a flange inclined to the plane of such side of the wheel, and a supporting bracket inwardly beyond the wheel, a rock-shaft journaled in said bracket on a line oblique to the plane of the wheel 35 and provided with an arm, and a roller revolvably mounted at the extremity of such arm, and means for imparting a rocking movement to said shaft and arm, for causing the roller to have an operative position substantially perpendicular to the face of said inclined flange and to frictionally bear on the latter, and to have a retired position of disengagement from such flange, said roller being provided with a plurality of flexible 45 members adapted to be centrifugally thrown for engagements under the tread of the wheel, and means for controlling the position of the rock-shaft.

11. The combination with a vehicle wheel, 50 and a fixed supporting part of the vehicle, of a rock shaft journaled in said support provided with an arm carrying a roller which is provided with a plurality of centrifugally operating flexible members, and said rock 55 shaft having a lever affixed thereto, another lever pivoted on the first named lever and having one member thereof forming a pawl and having a spring reacting between the other member thereof and the first lever, a 60 ratchet-like member on the support with which said pawl coacts, an operating lever and a connection between same and the second named lever, operable to permit the roller to frictionally engage the vehicle 65 wheel, and to swing and hold the roller in a

position withdrawn from engagement with the wheel.

12. A wheel provided vehicle having a fixed journal support, a rock shaft journaled in said support provided with an arm 70 carrying a roller which is provided with a plurality of centrifugally operating flexible members, and said rock shaft having a lever affixed thereto, another lever pivoted on the first named lever and having one member 75 thereof forming a pawl and having a spring between the other member thereof and the first lever, means for limiting the movement of the second relatively to the first lever, a ratchet-like member on the support with 80 which said pawl coacts, an operating lever and a connection between same and the second named lever.

13. A wheeled vehicle provided with a fixed journal support in suitable relation to 85 one of the vehicle wheels, a rockshaft journaled in said support provided with an arm carrying a roller which is provided with a plurality of centrifugally operated flexible members, means for controlling the rock-shaft whereby the roller carrying arm may be lowered to permit the frictional bearing of the roller on the vehicle wheel and for upwardly swinging and holding the arm for the retirement of the roller from its relation 95 to the wheel, and a spring clip or member which has, when the arm is lowered, a resilient engagement therewith for holding or 100 steadyng the roller in its frictional engagement with the wheel.

14. The combination with a wheel and the axle housing of a vehicle, which housing is provided with a forwardly extending bracket, a rockshaft journaled in said bracket in a line oblique to the axle and the 105 plane of the wheel, and carrying an arm of bowed shape, which arm is provided with a roller having a plurality of centrifugally operating flexible members, and said arm being adapted to be swung to a position for 110 presenting the roller in frictional engagement with the vehicle wheel and to be swung to a position of retirement crosswise of and in proximity to the axle housing, and means operable to permit the roller to engage the 115 wheel and to swing and hold the roller carrying arm in its upwardly withdrawn position.

15. The combination with a wheel and the axle housing of a vehicle, which housing is provided with a forwardly extending bracket, a rockshaft journaled in said bracket in a line oblique to the axle and the plane of the wheel, and carrying an arm of bowed shape, which arm is provided with 125 a roller having a plurality of centrifugally operating flexible members, and said arm being adapted to be swung to a lowered position for presenting the roller in frictional engagement with the vehicle wheel and to 130

- be swung to a position of retirement cross-wise of and in proximity to the axle housing, and provided at an intermediate portion, on its upper side with a buffer, and means for controlling the positions of the roller carrying arm.
16. The combination with a wheel and the axle housing of a vehicle, which housing is provided with a forwardly extending bracket, a rockshaft journaled in said bracket in a line oblique to the axle and the plane of the wheel, and carrying an arm of bowed shape, which arm is provided with a roller having a plurality of centrifugally operating flexible members, and said arm being adapted to be swung to a lowered position for presenting the roller in frictional engagement with the vehicle wheel and to be swung to a position of retirement cross-wise of and in proximity to the axle housing, and provided at an intermediate portion, on its upper side with a buffer, and means for controlling the positions of the roller carrying arm, and a resilient member with which the roller carrying arm engages when in its lowered position.
17. The combination of a wheel and a fixed supporting part of a vehicle, an arm journaled in said support and having its extremity in the form of a circular hub or boss provided with a downwardly opening socket therein, the wall surrounding said socket having radial apertures therethrough, a roller, having a plurality of centrifugally operating flexible members, provided centrally with a stud on which it rotates, and which stud is extended to fit said socket and is provided with recesses therein, a retaining member formed of wire, an intermediate portion of which is formed to embrace the extremity of the arm while the end portions of the wire are downwardly and then radially inwardly extended for detachably engaging in the apertures in the arm-extremity and in the stud, and means for controlling the positions of the roller carrying arm relatively to the wheel.
18. The combination of a wheel and a fixed supporting part of a vehicle, an arm journaled in said support and having its extremity in the form of a circular hub or boss provided with a downwardly opening socket therein, a wall surrounding said socket having radial apertures therethrough, a roller, having a plurality of centrifugally operating flexible members, provided centrally with a shouldered and upwardly opening hollow stud on which it rotates, and which stud is extended into said socket and is provided with recesses therein, a retaining member engaging the extremity of the arm and having members radially and inwardly detachably engaging in the apertures in the arm extremity and in the stud,—the cavity in the stud constituting a lubricant receptacle and the stud having a radial duct through the roller surrounded portion thereof, and means for controlling the positions of the roller carrying arm relatively to the wheel.
19. In a device of the character described, the combination with a vehicle wheel having a ring on the side thereof within the wheel rim, of a roller mounted on the vehicle and adapted to have frictional engagement with said ring and provided with a plurality of centrifugally acting flexible members.
20. In a device of the character described, the combination with a vehicle wheel having a ring on the side thereof within the wheel rim, of a roller mounted on the vehicle and adapted to have frictional engagement with said ring, provided with a plurality of centrifugally acting flexible members, and means for detachably connecting said ring on the wheel.
21. In a device of the character described, the combination with a vehicle wheel, of a roller adapted to be positioned in frictional bearing against the wheel suitably adjacent its ground bearing portion and provided with a plurality of centrifugally operating flexible members and swivels through the medium of which they are connected to the roller.
22. In a device of the character described, the combination with a vehicle wheel, of a roller adapted to be positioned in frictional bearing against the wheel suitably adjacent its ground bearing portion and provided with a plurality of centrifugally operating flexible members, each comprising at its portion adjacent the roller an elastic member having a swivel engaged therewith and which swivel is connected to the roller.
23. In a device of the character described, the combination with a vehicle wheel, of a roller adapted to be positioned in frictional bearing against the wheel suitably adjacent its ground bearing portion, provided with a plurality of centrifugally operating flexible members, each comprising a plurality of links, and a link connecting elastic member, and swivels for connecting the flexible members to the roller.
24. In a device of the character described, the combination with a vehicle wheel, of a roller adapted to be positioned in frictional bearing against the wheel suitably adjacent its ground bearing portion, provided with a plurality of centrifugally operating flexible members, each thereof comprising at its portion adjacent the roller an elastic rubber link and a swivel engaged with said link and relatively to which the latter is rotatable and which swivel is connected to the roller.
25. In a device of the character described, the combination with a vehicle wheel, of a roller adapted to be positioned in frictional bearing against the wheel suitably adjacent

its ground bearing portion, provided with a plurality of centrifugally operating flexible members, each thereof comprising at its portion adjacent the roller an annular elastic 5 rubber link having a metallic lining provided with lips engaging the opposite sides of the link and a shoulder provided swivel member extending radially through and beyond said lining and the body of the link 10 and connected with the roller.

26. In a vehicle the combination with one of the wheels thereof having a friction bearing ring, of a roller mounted to have the rim thereof in frictional bearing on said 15 ring and provided with a plurality of flexible centrifugally operating members, and a device for clearing or cleaning the surface of the friction ring mounted on the vehicle and adapted to have a position for engagement 20 with said ring.

27. In a vehicle the combination with one of the wheels thereof having a friction bearing ring, of a roller mounted to have the rim thereof in frictional bearing on said 25 ring and provided with a plurality of flexible centrifugally operating members, and a scraper blade mounted on a fixed part of the vehicle and to extend to engagement with the surface of the friction ring and adjustable whereby the position thereof may be 30 shifted from engagement to one of disengagement from the ring.

28. In a device of the character described, the combination with a vehicle, of 35 a roller provided with a plurality of centrifugally operating flexible members, a movable support on which the roller is mounted whereby it may be positioned in frictional contact on the wheel and retired 40 away from such wheel, means for varying the position of the support, and a housing mounted on the vehicle into which the roller may be entered when in its retired position.

29. In a device of the character described, 45 the combination with a vehicle, of a roller provided with a plurality of centrifugally operating flexible members, a movable support on which the roller is mounted whereby it may be positioned in frictional contact on the wheel and retired away from 50 such wheel, means for varying the position of the support, and a housing mounted on the vehicle having a side and end thereof

open, a spring hinged cover for closing such 55 open side and end and including a member to be engaged by the retiring roller whereby such cover will be automatically opened by the roller as it is moved into the housing.

30. In a device of the character described, 60 the combination with a vehicle, of a roller provided with a plurality of centrifugally operating flexible members, a movable support on which the roller is mounted whereby it may be positioned in 65 frictional contact on the wheel and retired away from such wheel, means for varying the position of the support, and a housing mounted on the vehicle having a side and end thereof open, a spring-hinged cover to 70 close the side of the housing having an angularly arranged and reversely curved end portion for closing the end of the housing, the extremity of such portion constituting an impingement member for opening 75 the cover when the roller is shoved into the housing, and the concave part thereof serving as a pocket for the reception of the roller-carried flexible members.

31. In a device of the character described, 80 the combination with a vehicle wheel, of a roller mounted adjacent the ground bearing portion of the wheel and adapted to have the edge thereof in frictional engagement 85 with the wheel and provided with a plurality of flexible centrifugally operable members, said roller being provided with a tire ring detachably connected thereto and having a tire thereon.

32. A flexible anti-skid member for a device of the character described, comprising 90 a swivel and means for attachment of the member to a roller.

33. A flexible anti-skid member for a device of the character described, made elastic 95 for endwise distention and contraction provided with a swivel, and means for attachment of the member to a roller.

34. A flexible anti-skid member for a device of the character described, comprising 100 a plurality of links, an end one of which is composed of elastic material, and having a swivel connected thereto which is provided with means for the attachment thereof to a roller.

WILLIAM H. PUTNAM.
